UNITED STATES PATENT OFFICE.

JOHN FEGGETTER BLAKE, OF NEW HAVEN, CONNECTICUT.

COIN-OPERATED DEVICE.

SPECIFICATION forming part of Letters Patent No. 637,700, dated November 21, 1899.

Application filed April 20, 1899. Serial No. 713,775. (No model.)

To all whom it may concern:

Be it known that I, JOHN FEGGETTER BLAKE, a citizen of the United States, residing at New Haven, in the county of New Haven, in the State of Connecticut, have invented new and useful Improvements in Coin-Operated Devices, of which the following is a specification.

This invention relates to coin-operated devices or "slot-machines," so called, and the invention resides in the novel features of construction set forth in the following specification and claims and illustrated in the annexed drawings, in which—

15 Figure 1 is a side elevation of the device sectioned along *v v*, Fig. 2. Fig. 2 is a section along *w w*, Fig. 1. Fig. 3 is a section along *xx*, Fig. 2. Fig. 4 is a section along *yy*, Fig. 1. Fig. 5 is a section along *zz*, Fig. 4.
20 In the drawings is shown a case or housing 1 of suitable shape and material, and 2 is a shaft. The handle or lever 3 when rocked or swung back and forth will actuate the arm 4, to which at 5 is pivoted or connected pawl 6, 25 adapted to engage ratchet 7. The pawl 6, moved back and forth, rotates the ratchet in one direction or gives a step-by-step rotation to such ratchet. The ratchet 7 has the teeth *a* and what may be called a "gap" or "tooth-less space," the distance from tooth *a'* to tooth *a''* being larger than the space between successive teeth, or, say, equal to the space occupied by two ratchet-teeth. If a filler, such as a coin 8, is held in position to fill this gap or 30 to form a tooth in the space *a' a''*, the pawl 6, taking hold of the coin as of a tooth *a*, will keep on rotating the ratchet or disk 7. If no coin is passed in, the gap *a' a''* being empty, the pawl 6, playing idly back and forth in this 35 gap, will leave the ratchet at rest.

The case 1 is shown with a slot or mouth 9, at which the coin can be inserted to pass along the guide or chute 10, having a yielding portion 11, for a purpose to be presently explained. From the chute the coin normally will slide or pass to the teeth *a*; but the ratchet 7 has a rim 12 for holding the coin in the chute or away from the toothed portion *a* of ratchet 7. Such rim, however, has a slot 40 or coin-holding portion 14, Fig. 5, which when opposite the coin in the chute receives such coin, so that the latter will pass or form a

temporary tooth in the gap *a' a''*. A suitable pocket or stop 15 at the slot or coin-holding portion 14 of the ratchet prevents the coin 55 dropping to the inner or center part of rim 12; but before the ratchet has completed a revolution the coin drops away from the ratchet and into the case 1 or into a suitable receptacle. To start a second revolution of the 60 ratchet, a second coin will thus have to be put in the slot 9. This rim 12, it is noticed, holds a coin in the chute away from the ratchet until the slot 14 registers with the coin in the chute. Should, therefore, the ratchet 65 have the slot 14 away from the chute when such coin is introduced, such coin will remain in the chute until the pawl 6 or the ratchet 7 has moved the slot or receiving portion 14 to the chute. The coin then entering the gap 70 *a' a''* to form a temporary tooth enables the pawl 6 to continue rotating the ratchet.

Should it occur that a coin enters only partly into slot 14, so as to still contact with or project toward the chute while being propelled by pawl 6, the yielding chute portion 11 by swinging or giving way will avoid breakage or allow the coin to pass on or rotate with the ratchet. This yielding chute portion while adapted to yield for the passage of a coin projecting laterally from or only partly received in the ratchet is normally in line or level with the main chute portion or body 10. The yielding portion can be formed in any suitable way. A spring-trap 80 or spring-hinge support has been found suitable for this yielding portion 11.

The ratchet 7 is shown with bars or rods 16, supported by said ratchet and by disk 17. This drum or carrier 7 16 17 can be made to 90 serve various purposes—as, for example, to carry pictures or faces 18 of an advertising device or stereopticon. Of course this actuating-disk 7 is not limited in its application to any particular apparatus, but can be applied wherever serviceable.

If the handle 3 causes the shaft 2 to oscillate or rock, then the drum 7 16 17 must be mounted loosely on the shaft, so as not to turn backward therewith, or the shaft 2 could 100 be made in two separate or independent sections, one for the handle and one for the drum, so that the handle and drum, with their respective shaft sections or pieces, are capa-

ble of motion or rotation independent of one another. A brake or friction appliance, such as a spring 19, can be made to prevent excessive or retrograde rotation or movement of 5 the ratchet. Suitable stops or studs 20 can be made to properly limit the throw of lever 3. The casing 1 may have one or more sight- openings or be otherwise adapted to its intended use. If a coin or filler 8 should be 10 permanently secured in coin-holder 14, it would make a perpetually-operative device.

What I claim as new, and desire to secure by Letters Patent, is—

- 15 1. A pawl and a ratchet having a gap or toothless space and a slot or coin holding portion adapted to hold a coin in position to fill the gap or form a tooth substantially as described.
- 20 2. A pawl and a ratchet having a gap or toothless space, a slot or coin holding portion and a rim for holding the coin away from the ratchet or teeth substantially as described.
3. A pawl and a ratchet having a gap or

toothless space, and a slot or coin holding portion, combined with a chute having a portion 25 normally in line or level with the main chute portion and made to yield for the passage of a coin projecting from the ratchet toward the chute substantially as described.

4. A pawl and a ratchet having a gap or 30 toothless space, a coin-holding portion, and a chute, said ratchet being provided with a rim made to hold a coin in the chute substantially as described.

5. A pawl and a ratchet having a gap or 35 toothless space, a coin-holding portion, and a brake or friction appliance for the ratchet substantially as described.

In testimony whereof I have hereunto set my hand in the presence of two subscribing 40 witnesses.

JOHN FEGGETTER BLAKE.
